UNITED STATES PATENT OFFICE

ROBERT A. THOMPSON, OF NEW ORLEANS, LOUISIANA

METHOD OF AND APPARATUS FOR BUILDING IMPROVED ROADS

Application filed May 15, 1928. Serial No. 277,954.

This invention relates to road and street constructions and has for its object to provide a method of, as well as an apparatus for, building improved roads and the like which will be more efficient and provide a less costly construction than methods and apparatuses heretofore proposed.

With these and other objects in view the invention consists in the novel steps and combinations of steps constituting the method as well as in the novel details of construction and combinations of parts constituting the apparatus, all as will be more fully herein-after disclosed and particularly pointed out in the claims.

Referring to the accompanying drawings forming a part of this specification in which like numerals designate like parts in all the views;

Fig. 1 is a side elevational view of an apparatus such as will carry out the method of this invention;

Fig. 2 is a detail of construction illustrating the means for variably adjusting the position of the smoothing rollers associated with this apparatus;

Fig. 3 is a top plan view, with some of the parts broken away and other parts shown by phantom lines, illustrating the apparatus shown in Fig. 1;

Fig. 4 is a vertical sectional view of the principal parts of the apparatus hereinbefore mentioned as viewed from a position between a smoothing roller and the rest of the apparatus;

Fig. 5 is a vertical sectional view taken through one of the smoothing rollers;

Fig. 5^a is a detail showing a modification in construction of a smoothing roller;

Fig. 6 is a partial longitudinal sectional view of the apparatus taken as on the line 6-6 of Fig. 3 and looking in the direction of the arrows;

Fig. 7 is a vertical sectional detail taken through some of the compressing disks to better illustrate the mounting thereof;

Fig. 8 is a horizontal sectional view taken through some of the compressing disks and taken as on the line 8-8 of Fig. 6, looking in the direction of the arrows;

Fig. 9 is a detail sectional view taken through one end of one of the tanks associated with this apparatus to illustrate a method of controlling the application of a lubricant to the compressing disks;

Fig. 10 is a diagrammatic illustration indicating the relationship of the two groups of compressing disks as well as the smoothing rollers and the effect had by each upon the roadway;

Fig. 11 is a transverse sectional view of a roadway as completed by methods and apparatuses heretofore known;

Fig. 12 is a transverse sectional view similar to Fig. 11 but illustrating the improved roadway resulting from the use of this invention;

Fig. 13 is an enlarged sectional view of a roadway made in accordance with heretofore known methods;

Fig. 14 is an enlarged detail sectional view of the action of the first group of compressing disks upon a roadway formation; and

Fig. 15 is a view of the parts shown in Fig. 14 after the second group of compressing disks and the following smoothing roller have passed thereover.

In order that this invention may be the better understood it is said that as a result of heretofore known methods employed in road construction, the layers of road material have not maintained the corelationship intended when subjected to traffic conditions. By this is meant that heretofore known methods have contemplated the superposition of one layer of road material upon another without providing positive interlocking of said layers. The obvious result has been that an upper layer "creeps" over an under layer. Other results have been a thinning of the road surface, in parts, under continued traffic with a further result that the roads soon have to be patched in spots, if not more completely built up.

By this invention the above mentioned ill-effects are avoided through the creation of a more positive and integral bond between the respective layers of the road, as a result of which a road made in accordance with this invention is more permanent and subjected

less to repairs than heretofore known roads. This result is attained through the employment of the apparatus now to be described.

Referring to Figs. 1 and 3 there is provided a rigid framework comprising side channel bars 1 joined at frequent intervals by structural subsidiary framing members 2 and upon which is suitably mounted an engine 3 of any desired type but preferably one involving power produced from internal combustion. 5 4 is a steering device connected as by the means 5 in a well known manner to lugs provided therefor on a front truck 6 of structural iron framework. Said truck may be 10 secured in position for movement of the vehicle in a straight line by the provision of a latch member 7, pivotally carried by the channels 1 and adapted to seat in a suitable notch in the framework of said truck, said 15 latch adapted to be actuated by a connecting rod 8 operated by a hand lever 9 provided with a detent disposed adjacent the driver's seat 10.

Power from the engine 3 is conducted 20 through the usual shaft connection, not shown, leading to a differential mounting in the box 15 therefor, and through said differential to two power shafts 16 and 17 each leading laterally therefrom. Near the outer 25 extremity of the shaft 16 is a sprocket 17 connected as by a drive chain 18 (passing over a take-up roller 19) to a sprocket 20 disposed on a shaft 21 the ends of which are mounted in the side channels 1 of the vehicle frame. 30 Near the outer end of the other drive shaft 17 is a sprocket 22 connected as by the chain 23 (passing over a take-up roller 24) to a sprocket 25 mounted on the other end of the shaft 21. The differential shafts 16 and 17 35 are supported by suitable brackets 26 to the frame of the vehicle.

Also mounted on the shaft 16 is a second sprocket 30 connected as by the chain 31 to a sprocket 32 mounted on one end of the rear 40 axle 33 of the vehicle, said axles being suitably supported in brackets on the rear truck 34, said rear truck being incapable of turning movement relative to the frame of the vehicle. Likewise mounted on the other differential shaft 17 is a second sprocket 35 connected as by the chain 36 to a sprocket 37 mounted on the other end of said rear axle 33, so that power from the engine will be positively transmitted to the rear axle.

55 This invention also features the transmission of power from said engine to the front truck of the vehicle in a manner presently to be described.

As before stated, the front truck 6 comprises a frame-work, and to the top of this frame-work there is rigidly secured, see Fig. 6, one member 40 of a hardened steel turn-table, the other member 41 of which is rigidly carried by cross framing of the body of the vehicle. Through the center of these two

turn-table members is disposed a short shaft 42 constituting the king-pin for the front truck. At the top of this shaft is rigidly secured a bevelled pinion 43 adapted to enmesh with a pinion 44 keyed to the transverse shaft 21 carried by the body of the vehicle and on which are mounted the sprockets driven from the differential shafts 16 and 17. At the lower end of the king-pin shaft 42 is securely mounted another bevelled pinion 45 adapted to enmesh with a pinion 46 keyed to a transverse power shaft 47 the ends of which are journaled in the side frame members of the truck 6, an additional supporting bracket 48 being provided adjacent the pinion 46. A 70 similar intermediate bracket 49 is provided for the upper transverse shaft 21. Near each outer end of the truck power shaft 47 is mounted a sprocket 53 connected as by a chain 54 with a sprocket 55 mounted on the axle 56 of the truck 6. Thus power is positively transmitted from the engine to the front truck regardless of the particular angle that said truck makes with reference to the body of the vehicle, all as will be readily understood from the drawings.

The front axle 56 has keyed thereto throughout its length a plurality of metallic disks 60 serving as wheels for the truck, each disk provided with a solid rim portion 61 of substantially uniform thickness. This rim portion is merged into a thickened hub portion 62 all as clearly indicated in detail in Figs. 7 and 8. The relationship, however, of the hub portion with the rim portion of each disk is such that one side of each disk is perfectly plane, the additional thickness of the hub portion serving as a means for spacing the rim portion of one disk from the rim portion of the next adjacent disk. Thus there is provided, as particularly shown in Fig. 4, a construction comprising a plurality of disks of the same diameter and same thickness so integrally mounted on a common shaft that there is provided a space 63 between the adjacent disks. As a result of this construction it will be evident that as this vehicle is moved over the road material, the weight of said vehicle will force the gang disks into said material.

The material which enters the spaces 63 as a result of this action is readily removable therefrom by the provision of a plurality of cleaners comprising fingers 64 mounted on diametrically opposite sides of the gang of disks as shown in Fig. 8, said fingers being secured in operative position by clamps 65 to supporting rods 66 carried by a suitable frame 67 extending rigidly from the truck 6 as clearly shown in Fig. 6.

The fingers 64 are of a length to clean the road material adhering to the disks from the rim portions thereof. In other words, the fingers extend inwardly between the disks to a point where the rim portion 61 begins

to merge into the thickened hub portion 62, and in order that the road material may not become clogged or unnecessarily packed at the end of the fingers, each disk 60 is provided with a plurality of transverse apertures 68 disposed between the rim and hub portions.

The rear truck 34 likewise has mounted on its axle 33 a plurality of disks 70, serving as wheels, which are exactly similar to the disks 60 of the front truck but the disks 60 and 70 are mounted in staggered relation. This is best illustrated in Fig. 10 wherein it will be observed that the disks 60 are moving to the right as indicated by the arrows in said figure producing in the road material a plurality of grooves 71 between which will be an upstanding ridge 72 of said material. In this figure it is to be understood that the front truck is locked by the latches 7 above described to the body of the vehicle so that the disks 60 are in parallel relation with the disks 70 of the rear truck. The disks 70, being staggered with relation to the disks 60, will work on the ridges 72, compressing the material thereof downwardly between the grooves 71 created by the forward disks 60. Between the rear gang disks 70 are provided the cleaning fingers 64 above described carried by a supporting rod 66 and a bracket 67 secured to the rear truck, substantially the same as the same parts above described, and the rear disks 70 are formed with rim and hub portions and apertures 68 exactly as were the disks 60.

Within the forward truck 6 is disposed either a single tank or a plurality of tanks such as indicated at 75 disposed on either side of the pinion 46 and alongside the shaft 47 carrying the same. These tanks are secured to the truck in any suitable manner as by the straps 76 secured to the platform or cross-framing member 77. These tanks are particularly illustrated in Figs. 1, 3, 4, 6 and 9 from which it will be observed that each tank is provided in its bottom portion with a common pipe 78 provided with outlets including a plurality of nipples 79 which extend downwardly through the bottom wall of each tank as well as through apertures provided therefor in the platform 77. These nipples are spaced from each other in accordance with the spacing of the disks 60 so that lubricant from said tank 75 may drip onto one of the side faces of each disk. The tank is filled with lubricant through a suitable filler opening 80 in the top thereof and is permitted to enter the pipe 78 in any convenient manner. In Fig. 9 is shown a valved arrangement for controlling the escape of the lubricant from the tank and which comprises a plug 81 fitting said pipe and secured at the end of a valve stem 82 which is screw threaded through the wall of said tank to move said plug so as to cover or uncover the entrance

83 to said pipe. Said entrance may be conveniently located in the top of the pipe 78 or it may be disposed at a lower level as desired.

By providing an entrance at both ends of said pipe any uneven locomotion of the apparatus over the roadway under construction will not necessarily interrupt the discharge of the lubricant to the disks. That is to say, a more even distribution of the lubricant is obtained by such a device than would be the case were the nipples directly connected to the interior of the tanks. Further, one outlet from the tank is to be preferred over a plurality of outlets therefrom, as it is often desired to prevent lubricant passing to the disks and by this construction no more than two cut-offs are required. A still further advantage, lies in the fact that the lubricant can be supplied to both tanks through either tank by merely opening the valves thus equalizing the amount of lubricant in the tanks. The lubricant is preferably supplied to the flat side of the disks as it has been found that the road material has a tendency to adhere to this side to a greater extent than it does to the other side. It is to be understood that the lubricant within the tanks 75 is for the purpose of preventing to a minimum the adhesion of sticky road material to the disks and will not be used when such material is not a part of the specifications. There is provided a valve stem such as 82 for each of the tanks to control the flow of oil therefrom.

In the rear truck 34 of this apparatus there is provided a tank 84 for lubricant such as contained in the tank 75 but there is no necessity of having more than one tank in said rear truck because there is no interfering mechanism such as the intermediate drive shaft 47 with its attached pinion 46 as above described.

The tank 84 is likewise provided with a filler opening 80 and a valve 82 controlling the flow of the fluid from the tank through a plurality of nipples 79 quite similar to the corresponding parts above described.

This apparatus is provided with a smoothing roller 90 disposed in advance of the forward truck 6 said roller being preferably made of steel tubing of a diameter substantially less than the diameter of the compacting disks carried by the truck 6. Said roller is mounted between the extremities of side framing bars 91 of channel or I-beam iron, with cross braces 92 for additional strength. These side bars 91 extend obliquely upwards from the roller 90 to the end of the chassis or side channel frame members 1 of the body of the vehicle, and one of said bars is bent to provide a lever portion 92 extending towards the middle of the apparatus (see Fig. 1). At the bend of this bar there is provided a shaft 93 to which both of said bars are keyed as at 94, said shaft extending transversely

across the end of the chassis of the apparatus. The free end of the lever portion 92 of the bar 91 passes into a box formed by a bracket 95 rigidly secured to the side of the chassis, (see Fig. 2) and through the top of said box, as well as through the upper flange of the channel member 1 of the chassis, is a screw 96 provided at its top with a hand wheel 97 and whose lower end is adapted to engage the top surface of the lever 92. It thus results that the forward smoothing roller 90 may be raised or lowered by swinging it together with its supporting frame about the pivot shaft 93 by action of the screw 96. This is very desirable in finishing the surface of the prepared road.

There is also provided a smoothing roller following the rear truck 34 which is mounted on a frame comprising side channels or I-beams both of which extend obliquely upwards to a pivot shaft, but only one of which is bent and extended along the chassis, said roller and associated parts being exactly similar to the same parts above described and therefore identified by the same numerals in the drawings. It is to be observed from Fig. 3 however that the lever portion 92 of the rear roller is extended along the side framing channel 1 on the opposite side of the apparatus from the similar member above described, but that it has its free end disposed within a box through the top of which operates a screw controlled by a hand wheel exactly the same as the parts 95, 96 and 97 hereinbefore mentioned. Thus each smoothing roller is capable of vertical adjustment independently of the other.

Each of the frames, supporting the smoothing rollers, is provided with a platform 100 disposed in a substantially horizontal plane and to which is fastened a tank 101 for fuel oil as by the straps 102. The end of each tank is connected as by a pipe 103, provided with a valve 104, to the rear end of its associated roller 90, the end of said pipe entering the internal portion of each roller and provided with a nozzle 105 constituting a burner. It will thus be seen from Fig. 5 that a valved pipe 103 leads into each end of a smoothing roller to control the oil flow thereto. By this construction it is possible to heat either or both ends of each roller to either equal or unequal temperatures. The ends of each roller are provided with spiders 106 provided with an extending hub by means of which the roller is ventilated and supported within the side bars 91.

The end of each pipe 103 within a tank 101 is downwardly extended, opening near the bottom of the tank, so that a siphoning of the oil from the tank is permitted to the burner nozzles 105 as clearly shown in Fig. 6. This construction insures a steady and uninterrupted flow of oil regardless of usual inequalities in road surface as a result of

which the burners will remain lighted so long as the valves 104 are open.

From the foregoing description of the apparatus and with particular reference to Figs. 10 to 15 inclusive it will now be seen that there is provided a novel method of road construction producing better results than prior known methods. In Fig. 11 is illustrated a transverse sectional view of a roadway as completed by heretofore known methods and from which it will be seen that substantially no bond is formed at 110 between the roadway base 111 and the intermediate road layer 112, nor is there provided an effective bond 113 between said intermediate layer and the top layer 114. By this is meant that the base has been graded by scrapers and then rolled so that the top surface thereof is substantially smooth. The material of the intermediate layer was then applied over this surface and raked and/or rolled, with the ultimate result that its upper surface likewise was comparatively smooth.

The rollers used in road construction have been of substantially tubular formation with smooth surfaces and therefore equal pressure was applied to all parts of each layer rolled, particularly in view of the fact that said rollers were of large dimension generally being 6 feet from end to end.

Therefore when the top or finishing layer was applied to the intermediate layer and rolled, there were created as at 110 and 113 plane surface contacts between the adjacent layers. It resulted therefore, upon continued traffic over such a constructed road, that one layer would "creep" over the underlying layer, creating humps and hollows to the end that the top layer 114 soon became very thin in spots, and in fact wore entirely through.

In Fig. 12 is shown, on the other hand, a transverse sectional view of a roadway as prepared in accordance with this invention, and with additional reference to Fig. 10 it will be evident that after the compressing disks of the apparatus above described have passed over the roadway base 111, the top surface of said base will not be smooth but will be substantially corrugated as indicated at 115, it being understood that the smoothing rollers 90 of said apparatus will be raised by the hand wheels 97 out of effective contact with the road. This is due to the fact that the advancing or forward compressing disks 60 will be forced, by the weight of the apparatus, down into the material of the base 111 of the road, putting a very substantial pressure on said material immediately under each of the compressing disks 60. In the continued travel of the apparatus, the following compressing disks 70, which are in staggered relation with the forward disks, will work upon the ridges 72 resulting from the compression by the forward disks, but inasmuch as the base material has been fully

compressed under the grooves 71, the action of the disks 70 will only tend to compress the material of said ridges to the same degree as the material under said grooves. The result is that the base material is given a certain amount of compression in spaced vertical planes by the forward disks, and a compression of less amount by the following disks in vertical planes between said first mentioned planes, thus producing an irregular or corrugated surface as at 115.

The intermediate layer 112 is then applied over the base and subjected to the same rolling action with the result that the forward disks 60 place the material of said layer under a certain compression which is followed by the compression of said material to a lesser degree by the following disks 70 and in vertical planes intermediate the application of pressure by the forward disks. The apparatus is of course rolled over the roadway alternately in opposite directions and in this continued application of pressure through the disks, the material of each layer is subjected to repeated pressures which tend to shift said material laterally as a result thereof. It will therefore be evident that the surface of the intermediate layer will also be corrugated when the top or finishing layer 114 is applied thereto.

This top layer is likewise subjected through the disks to compression by the apparatus alternately in parallel vertical planes, with the result that the material of the intermediate layer which has received most compression, resulting in a groove, will receive the material of the top layer under pressure tending to force the material of the top layer downwardly into said groove. There is of course a limit to the amount of pressure which can be applied in this direction and therefore the remaining pressure is laterally distributed, causing the material of the top layer to co-mingle, to a greater extent than heretofore known, with the material of the intermediate layer. The action of this compression will create a result similar to that obtained by raking the surface of the ground, then applying a thin layer of a different kind of soil thereover, and then drawing the teeth of the rake through the top soil except that by this invention there is provided a tremendous vertical pressure due to the weight of the apparatus.

These results are particularly brought out in Figs. 13 to 15 where, by the method of shading employed in the drawing, the compression of the materials as well as the irregularities in the joints between the layers thereof is made clear. Referring to Fig. 14 it will be seen that the pressure applied by the disks 60 in forming the grooves 71 not only affects the material thereunder of the top layer, as indicated by the heavy shading at 120, but this pressure is transmitted downwardly to

the particles of the material of the intermediate layer therebelow, thus additionally or further compressing the same as indicated at 121. This results in an accentuation of the irregular or corrugated bond 116 to deepen the depressions of said corrugations as at 122. When the following disks 70 reach and work upon the ridges 72 between the grooves 71, the material will have become so compacted at 120 that the material under each ridge 72 can not be compressed to the same degree, since the compacted mass at 120 is too dense to yield sufficiently for this purpose.

It therefore results that the accentuated corrugated bond at 116 shown in Fig. 14 is slightly smoothed out but still remains quite irregular as shown in Fig. 15. It is to be understood of course that the same results are obtained at both 115 and 116 inasmuch as the same method of construction is employed. The smoothing rollers 90 are brought into use for action on the top layer of material to break down or flatten the upstanding ridges 72 while at the same time furnishing additional pressure, and in this respect it should be stated that these smoothing rollers have been found so effective in combination with the results accomplished with the gang disks above mentioned that it is not necessary to employ the usual heavy-duty road rollers to produce the smooth finish 117. The results obtained by this improved roller construction are a very irregular but corrugated bond such as 116 between the adjacent layers which differs materially from the relatively plane bond such as 113 obtained by heretofore known methods, and a relatively smooth finishing surface on the top layer which grows smoother with traffic.

The effect of this improved method of construction is a "mincing" one, except that the materials of each layer are not entirely mingled. The disks, being separated and of not too great a width, are forced by the weight of the apparatus to a substantial depth into the road materials. Further no disk can drag due to the fact that not only are all the disks of one group keyed to a common shaft but the shaft of each group is directly connected to the engine, resulting in a true translation of weight into pressure which is always directed vertically to the road materials. Therefore, no horizontal displacement of said material can take place under construction except the relatively small amount thereof caused by the deflection of part of the vertically applied pressure, which only tends to more firmly compact said material.

In Figs. 6 and 8 it is to be particularly observed that each of the fingers 64 serving as cleaners for the material collecting between the disks, are secured to their supporting rods 66 by the set screws or other clamping device 65. This is for the purpose of permitting

said fingers to be loosened on their shafts and swung to adjustable position either upwardly or downwardly between the disks. In other words, when this apparatus is being used on road material which has a tendency to cling to the sides of the disks such for example as clay or wet earth the cleaners will be placed in full operative position as shown in Fig. 6 but when the nature of the road material is such that there is little or no adhesion of the same to the disks then said cleaners will be moved about their shafts to any desired position including entire disengagement with said disks. It has been found in practice that when the oil drip or lubricant is applied to the disks it is unnecessary to use the cleaning fingers as the oil or other lubricant will so affect the surface of the disks as to cause little or no adhesion of the road material thereto. Particularly is this the case when the apparatus is being used in bituminous road material at which time the lubricant of the disks is particularly advisable.

This method is not to be confused with those in which spaced disks not directly driven are employed. In such heretofore known methods the results herein described are not possible due to the drag of each disk, whereas the apparatus here disclosed is designed to overcome said drag by positively rotating each disk as it moves along the road. When a disk apparatus, not so powered as this apparatus, is used there is a very considerable amount of friction to be overcome which causes each disk to be bodily moved longitudinally of the road which pulls the material being worked and does not positively compress the same. This apparatus on the other hand does not move the material longitudinally but creates a downward pressure on the same which starts the moment that the disks come into contact therewith.

Neither is this method to be confused with those wherein an apparatus is used having spaced disks not keyed to their supporting shaft, or disks which are permitted bodily movement vertically to compensate for resisting pressures from the road material. When the disks are not keyed to their shafts, the longitudinal body movement thereof, above described, is more pronounced as will be evident. Disks designed for resisting pressure compensation are most unsatisfactory as they are permitted to rise bodily out of axial alignment with their companion disks as a result of which the road material as a whole is not given the degree of compression which it should receive. Also with these last named disks it is not possible to give to said material a uniformity of mass with the result that "soft spots" are left in said material which soon cause uneven traffic wear with subsequent breaking and necessary repairs at said spots. The apparatus herein described over-

comes these difficulties and objections by keying all of the disks to a common shaft so that each receives the same rotating driving force which is delivered to both ends of said shaft. Further, since none of the disks of this improved apparatus can be moved from axial alignment with their companion disks the road material is given uniformity of compacted mass and hence no possible formation of "soft spots," resulting in a much firmer road, requiring minimum upkeep and repair.

In Fig. 5^a is shown a modification in construction of the smoothing roller, wherein coaxial cylinders 130 and 131 of different diameters are employed to create a chamber 132 therebetween which may be substantially filled with sand as through a filler opening adapted to be closed by a plug 133 in the web portion of the spider 134. Heat from the burner 105 will be transmitted through the inner shell or cylinder 131 to the sand, which will uniformly retain said heat over a relatively long period of time, as a consequence of which the consumption of fuel oil by the burner may be materially lessened, as will be readily understood. The space 132 may be of any desired dimension, practical results having been obtained with a spacing of two inches.

From the foregoing it will thus be seen that by this invention there is provided a method of constructing a road having uniform mass compression which consists in working each layer to positively compact the particles thereof as well as to co-mingle the particles of two adjacent layers at the joint therebetween so that there is created a bond between said two adjacent layers which will prevent a creeping of the upper layer over the lower layer under traffic conditions. This bond is created while working the upper layer and said bond is of substantial corrugations transversely of the road. The pressure is positively applied by this method to the road materials and in successive steps by the two groups of compressing disks in such manner that the second pressure is applied to the particles of the material between the particles of the material which had been compressed by the first group of disks so that it can be truly stated that the pressures are applied in spaced planes successively. The rollers used in conjunction with the compressing disks apply additional pressure, which may be varied through the medium of the lever extensions of the side supporting frames thereof, to the topmost layer, and said additional pressure is applied together with heat.

The above mentioned steps of the method are accomplished through an apparatus having in combination a frame supported by two axles, a source of power carried by said frame, positive drive connections between said source of power and the ends of each

axle; a plurality of spaced disks constituting propelling means for the apparatus said disks being adapted to rotate with each axle and supporting the same, the disks of one 5 axle being staggered with respect to the disks of the other axle, adjustable cleaners for said disks, means for steering the apparatus, and means to lock said axles in parallelism. The descriptions of the apparatus above given 10 clearly bring out these elements. It is particularly to be observed that the forward axle 56 is rotatably associated with the chassis while the rear axle 33 is unrotatably associated therewith, and that the means for positively transmitting power from the engine 15 on the chassis to each of the axles includes a means for transmitting the power to the front axle including the vertical power shaft 42 which serves as a king pin to permit the 20 rotatable relation between the chassis and the forward axle 56. The apparatus is provided with interchangeable means to prevent the road material from adhering to the compressing disks said means including the fingers 25 64 and the lubricant supply from the tanks 75 and 84.

It is obvious that those skilled in the art may vary the details of construction constituting the apparatus as well as the steps 30 constituting the method without departing from the spirit of the invention and therefore it is not desired to be limited to the foregoing except as may be demanded by the claims.

What is claimed is:—

- 35 1. The method of constructing a road having uniform mass compression which consists in working each layer to positively compact the particles thereof; and creating a corrugated bond between two adjacent layers while working the upper layer by alternate compressions applied substantially simultaneously to prevent creeping of a layer over the one therebeneath under traffic conditions.
- 40 2. The method of constructing a road made up of layers of different materials which consists in positively applying to the particles of the material of each layer successive and substantially simultaneous alternate pressures, the pressures applied to a superposed layer causing the particles thereof to create a transversely corrugated bond with the particles of the adjacent supporting layer.
- 45 3. The method of constructing a road made up of layers of different materials which consists in positively applying pressure to some of the particles of the material of each layer in spaced planes, and successively and positively applying pressure to the other of said particles in planes between said first named planes, the pressures applied to a superposed layer causing the particles thereof to create a comingling transversely corrugated bond with the particles of the adjacent supporting layer.
- 50 4. The method of constructing a road made up of layers of different materials which consists in positively applying successively to the particles of the material of each layer alternate and substantially simultaneous pressures, the pressures applied to a superposed layer causing the particles thereof to create a transversely corrugated bond with the particles of the adjacent supporting layer; and preventing a vertical displacement of the compacted material as the pressures are removed.
- 55 5. The method of constructing a road made up of layers of different materials which consists in positively applying to the particles of the material of each layer successive alternate pressures, the pressures applied to a superposed layer causing the particles thereof to create a transversely corrugated bond with the particles of the adjacent supporting layer; and substantially simultaneously applying additional pressure to the topmost layer.
- 60 6. The method of constructing a road made up of layers of different materials which consists in positively applying to the particles of the material of each layer successive alternate pressures, the pressures applied to a superposed layer causing the particles thereof to create a transversely corrugated bond with the particles of the adjacent supporting layer; preventing a vertical displacement of the compacted material as the pressures are removed; and applying variable additional pressure together with heat to the topmost layer.
- 65 7. A road rolling apparatus having in combination a frame supported by two axles; a source of power carried by said frame; positive drive connections between said source of power and each axle; a plurality of spaced disks adapted to rotate with each axle and supporting the same; means for steering said apparatus; and means to lock said axles in parallelism.
- 70 8. A road rolling apparatus having in combination a frame supported by two axles; a source of power carried by said frame; positive drive connections between said source of power and the ends of each axle; a plurality of spaced disks constituting propelling means for the apparatus said disks adapted to rotate with each axle and supporting the same; adjustable cleaners for said disks; and means for steering said apparatus.
- 75 9. An apparatus for compacting the materials of roads under construction the same including a group of spaced compressing disks mounted for rotation with a common axle; a second group of spaced compressing disks mounted for rotation with another common axle; a chassis unrotatably associated with the axle of said second group but rotatably associated with the axle of said first

130

- mentioned group of disks, the disks of said first and second groups adapted to lie in alternate vertical planes when their axles are parallel; means to secure said axles in parallel relation; means to move the axle of the first group out of parallel relation with the other axle; and means to positively transmit power from a source located on said chassis to each of said axles regardless of their positions.
- 10 10. An apparatus for compacting the materials of roads under construction the same including a group of spaced compressing disks mounted for rotation with a common axle; a second group of spaced compressing disks mounted for rotation with another common axle; a chassis unrotatably associated with the axle of said second group but rotatably associated with the axle of said first mentioned group of disks, the disks of said first and second groups adapted to lie in alternate vertical planes when their axles are parallel; means to secure said axles in parallel relation; means to move the axle of the first group out of parallel relation with the other axle; and means to positively transmit power from a source located on said chassis to each of said axles regardless of their positions said means including means to permit said rotatable relation between said chassis and said first named axle.
- 15 11. An apparatus for compacting the materials of roads under construction the same including a group of spaced compressing disks mounted for rotation with a common axle; a second group of spaced compressing disks mounted for rotation with another common axle; a chassis unrotatably associated with the axle of said second group but rotatably associated with the axle of said first mentioned group of disks, the disks of said first and second groups adapted to lie in alternate vertical planes when their axles are parallel; means to secure said axles in parallel relation; means to move the axle of the first group out of parallel relation with the other axle; and means to positively transmit power from a source located on said chassis to each of said axles regardless of their positions said means including means comprising a vertical power shaft serving as a kingpin to permit said rotatable relation between said chassis and said first named axle.
- 20 12. An apparatus for compacting the materials of roads under construction the same including a group of spaced compressing disks mounted for rotation with a common axle; a second group of spaced compressing disks mounted for rotation with another common axle; a chassis unrotatably associated with the axle of said second group but rotatably associated with the axle of said first mentioned group of disks, the disks of said first and second groups adapted to lie in alternate vertical planes when their axles are parallel; means to secure said axles in parallel relation;
- 25 means to move the axle of the first group out of parallel relation with the other axle; means to positively transmit power from a source located on said chassis to each of said axles regardless of their positions; and interchangeable means to prevent said material from adhering to said disks.
- 30 In testimony whereof I affix my signature.
- 35 ROBERT A. THOMPSON.
